United States Patent Office

Des. 192,988
Patented June 5, 1962

192,988

PRINTED PLASTIC SHEET MATERIAL

Sheldon Silverman, Massapequa, N.Y., assignor to Southbridge Plastic Products, Inc., New York, N.Y., a corporation

Filed Feb. 2, 1961, Ser. No. 63,800

Term of patent 3½ years

(Cl. D87—3)

Fig. 1.

FIG. 2.

FIG. 1 is a plan view of a printed plastic sheet material showing my new design; and

FIG. 2 is an enlarged plan view of a portion thereof. A horizontally-repeating unit is enclosed within the vertical dot and dash lines and the design repeats vertically as shown.

I claim:

The ornamental design for a printed plastic sheet material, substantially as shown and described.
